UNITED STATES PATENT OFFICE.

GUNNAR CHRISTIAN EKSTRÖM AND GUSTAF ÖRSTRÖM, OF STOCKHOLM, SWEDEN, AS-SIGNORS TO AKTIEBOLAGET GERH. AREHNS MEKANISKA VERKSTAD, OF STOCKHOLM, SWEDEN, A CORPORATION OF SWEDEN.

MACHINE FOR MANUFACTURING PACKETS, FOR PACKING CIGARETTES OR OTHER MATTERS.

Application filed July 7, 1921. Serial No. 483,064.

To all whom it may concern:

Be it known that we, GUNNAR CHRISTIAN EKSTRÖM, a subject of the King of Sweden, and resident of Eriksbergsgatan 14, Stockholm, in the Kingdom of Sweden, and GUSTAF ÖRSTRÖM, a subject of the King of Sweden, and resident of Palsundsgatan 6, Stockholm, in the Kingdom of Sweden, have invented certain new and useful Improvements in Machines for Manufacturing Packets, for Packing Cigarettes or Other Matters, of which the following is a specification, reference being had therein to the accompanying drawing.

For packing cigarettes or other matters double capsules, packets, boxes or the like sometimes are used, the inner capsule or lining being generally of tinfoil. This invention relates to an arrangement in machines specially of the type, stated in the U. S. Letters Patent No. 1,379,254, by means of which the said machines may make also double packets etc.

In the accompanying drawing Figs. 1 and 2 show diagrammatically so much of a machine arranged in accordance with this invention, as is necessary to explain the invention; the said figures show the parts of the machine in different positions.

1, 1 . . . are mandrels, which are moved in an endless path in the direction indicated by the arrow and around which the sheets of tinfoil and the sheets of pasteboard, paper or the like are folded to form capsules etc. For making the inner capsule of tinfoil or the like the machine according to this invention is provided with an additional folding device, which, in relation to the motion direction of the mandrels, is located before the ordinary device folding the sheets of paper round the mandrels. In the drawing the two folding devices, designated by A and B, are of the same construction. A strip of tinfoil 2 together with a strip of thin paper sustaining the tinfoil strip are pulled by two feed rollers 3 and 4 from a reel 5 and are placed in the front of a support 6 and two folders 8 and 9 located at the same flush with the said table, the said strips being then cut off by a knife 7 fixed to a swingable arm and actuated in any suitable manner. The sheets of tinfoil and papers thus cut from the strips are moved by one of the mandrels 1 into the

space between the two folders 8 and 9 and are forced against the sides of the mandrel, as shown in Fig. 2, during which operation two rollers 10 and 11, carried by swingable spring actuated arms 12 and 13 bear against the sides of the mandrel and force the sheets against the same. During the folding operation a third roller 15, carried by a swingable, spring actuated arm 14, forces the sheets against the front side of the mandrel. When the mandrel has arrived to the position shown in Fig. 2, it stops, whereupon the folder 9 forces the one edge part of the sheets respectively inwards to the mandrel 1. The other edge parts of the sheets are then forced inwards by the folder 8, so that the said edge parts are brought into the position shown at the position *a* of the mandrel, Fig. 2. A presser 16 belonging to the mandrel and partaken in its motion, is then forced towards the mandrel and keeps the edge parts of the sheets in folded position. When the mandrel has arrived to the position *a*, which takes place, as the next mandrel arrives to the position, in which the edge parts of the next sheets are folded by the folders 8 and 9, three of the bottom flaps of capsule 80 are folded by folders 17, 18 and 19. Folders 17 and 18 are carried by swingable arms, which are provided with toothed segments 20 and 21, meshing with each other, and are actuated by an arm 22, acted upon by a spring and cam disk, not shown. Folder 19 is carried by a swingable arm, which is actuated by an arm 23, acted upon by a spring and cam disk, not shown. Folders 17 and 18 force inwards the narrow bottom flaps, 90 whereupon the folder 19 forces inwards one of the broad bottom flaps. The second broad bottom flap is left in outstanding position, while the mandrel together with the capsule passes to the folding device B. On the folders of the said device B a sheet of paper 24, adapted to form the outer capsule, previously has been placed. The folding of the said sheet 24 around the mandrel carrying the capsule of tinfoil is effected in just the same manner as described above with reference to the sheet of tinfoil. While the paper sheet is folded round the mandrel the presser 16 is removed from the mandrel in order not to be in the way of the folders. When the mandrel leaves the folding device B, the paper

sheet is folded round the mandrel, as shown in the position *b* of the mandrels, and the presser 16 keeps all the edge parts forced against the mandrel. One of the edge parts 5 of the paper sheet is provided with paste, so that the capsule is closed permanently. The bottom flaps of the paper capsule are then folded. Preferably the folding device adapted therefore is so arranged, that it first folds 10 the narrow paper flaps and then the unfolded tinfoil flap together with the adjacent paper flap, and finally the second paper flap, which, provided with paste, is fixed to the paper flap previously folded, one of the tinfoil flaps being thus simultaneously fixed so 15 that it holds the tinfoil capsule in its position inside the paper capsule.

Owing to the fact that the folding operations are effected simultaneously at *A* and 20 *B* and the folding of the bottom flaps of the tinfoil capsule takes place, while the mandrels are at a standstill at *a* and *b*, the additional folding device does not cause any delay in the operation of the machine, but the 25 output of the machine is the same as when single capsules are made.

The invention may, evidently, be modified

in some respects without exceeding the limits of the same. The machine may be used 30 also for the manufacturing of double packets, boxes or the like adapted for other articles, the inner capsule being then made for instance of impregnated paper.

We claim,

In a machine for making packets for containing cigarettes and the like, the combination of a plurality of mandrels movable in an endless path, and two sets of folders, one set of the folders being located behind the other set in the path of the mandrels, the 40 mandrels successively passing through the said folders and the first set of folders serving to fold a sheet of tinfoil around each of the mandrels and the second set of folders serving to fold a sheet of paper around each 45 mandrel carrying a folded sheet of tinfoil.

In testimony whereof we have affixed our signatures in presence of two witnesses.

GUNNAR CHRISTIAN EKSTRÖM.
GUSTAF ÖRSTRÖM.

Witnesses:

INEZ VOERSON,
STINA LARSON.

DISCLAIMER

1,499,204.—*Gunnar Christian Ekström and Gustaf Örström, Stockholm, Sweden.*
MACHINE FOR MANUFACTURING PACKETS FOR PACKING CIGARETTES OR OTHER
MATTERS. Patent dated June 24, 1924. Disclaimer filed February 4, 1930,
by the assignee, by mesne assignments, *Arenco Machine Company, Inc.*

Hereby disclaims from the claim of said Letters Patent No. 1,499,204 any machine for making packets for containing cigarettes and the like, embodying the combination recited in the claim, except where the first or additional set of folders "serving to fold a sheet of tin-foil around each of the mandrels" is constructed and arranged to fold the sides and a part of the bottom of the sheet of tin-foil and the second set of folders "serving to fold a sheet of paper around each mandrel" is constructed and arranged to fold the sides of the sheet of paper and to interfold the rest of the bottom of the sheet of tin-foil with the bottom of the sheet of paper, whereby the tin-foil capsule is fixed in its position inside the paper capsule.
